BRAKING APPARATUS

Steve Schnell, St. Louis, Mo., assignor to Wagner
Electric Corporation, St. Louis, Mo., a corpora-
tion of Delaware

Application February 26, 1932, Serial No. 595,259

5 Claims. (Cl. 188—78)

My invention relates to braking apparatus and particularly to expanding brakes of the "band" type, its principal object being to provide a brake of this type so constructed as to afford improved 5 and more uniform distribution of shoe pressure and thus secure better braking efficiency, more uniform lining wear, and less tendency to produce "squeaks" during brake application.

Other objects and advantages of my invention will become apparent from the following description taken in connection with the accompanying drawings in which Figure 1 is a side elevation of a preferred embodiment of my invention; Figure 2 is a bottom view of my improved brake band; Figure 3 is a cross sectional view of the band on the lines 3—3 of Figure 1; Figure 4 is a cross sectional view on the line 4—4 of Figure 1; Figure 5 is a side elevation of a modified form of brake band; Figure 6 is a cross sectional view of the band on the line 6—6 of Figure 5; and Figure 7 is a side elevation of another modified form of brake band.

Referring to Figures 1 to 4 inclusive, numeral 1 indicates the drum of the brake which is secured in the usual manner to the wheel of the vehicle and is enclosed on its open side by the backing plate or support 2 (Figure 4) secured to some fixed part of the vehicle. The brake shoe 3 is of the band type and is mounted within the drum and adapted to have its free ends expanded into engagement with the drum by suitable means, such as the hydraulic mechanism 4. The band is biased to "off" position by the usual spring 5, its "off" position clearance being determined by the adjustable stops 6. The brake band disclosed, is of the T-section type, comprising a lining carry-flange 7 and an integral web 8.

In band brakes of uniform cross section and provided with an anchor located approximately 40 at the center of the band, it is well known that when the drum is rotating and the band is engaged with the drum there will be greater pressure between the band and the drum at some 45 points than at others. For instance, if the drum is rotating in the direction of the arrow (Figure 1) the greatest pressure will occur at the central part of the shoe and the minimum pressure at a point approximately 60 degrees to the rear thereof. The maximum pressure at the central 50 part of the band is due to the "wrapping effect" and the uneven bending movement of the band when applied to the drum, and the relatively low pressure at the 60 degree position mentioned, results from the reaction of the wrapping effect 55 on this portion of the band tending to separate

it from the drum, and to the fact that the revolving drum produces the reverse of a wrapping effect at this point. The pressure at the point just referred to can be increased by the use of a combined anchor and radial pressure producing device of the type, for example, which is disclosed in the application of Steve Schnell, Serial No. 541,355. This device, indicated at 9, comprises a plate member 10 spaced from the backing plate by spacers 11 and secured thereto by 10 suitable means, such as rivets. A pair of plates 12 (one only being shown in Figure 1) are secured to the sides of the web 8 of the band between which the plate 10 extends. The outer edge of the plate 10 is provided 15 with an inclined surface 13 which cooperates through a roller 14 with approximately parallel surfaces 15 on the plates 12. It is thus seen that when the band is engaged with the drum it has slight circumferential movement 20 therewith which causes the inclined surfaces 13 and 15 to cooperate through the roller 14 to produce an outward radial pressure on the band to force it into tighter contact with the drum. A tension spring 17 maintains the roller in contact 25 with the inclined surfaces.

The placing of the combined anchor and radial pressure applying device at the point shown, increases the maximum pressure on the band near the central portion due to increase of the "wrapping effect" resulting from increased distance from the "forward" end of the band to the anchor. This condition is undesirable since it tends to distort the drum and to produce brake friction noise ("squeaks") and causes rapid lining wear. 30 To decrease this pressure, I propose to increase the flexibility of the band at this point, which may be accomplished, for example, by cutting away a portion of the flange 7 on each side of the web 8, as shown in Figures 2 and 3. The 40 amount of flange to be cut away is, of course, dependent upon the character of the band material and the degree of flexibility desired.

The increasing of the flexibility of the brake band at the central part results in a marked advantage in the action of the brake as a whole. It not only reduces the pressure at this point, but decreases the bending or distortion force necessary to initially engage the ends of the band with the drum by means of the actuating mechanism and gives the brake band an approximation of the action of the two-shoe hinged type of brake in this respect. As shown, the lining 18 may be entirely eliminated at the cut away portion of the flange, thereby saving a considerable 55

amount of lining material with little or no loss in braking effect. By my improved brake band, in combination with a combined anchor and radial pressure producing device, I am able to produce a very effective brake which is quiet in operation.

In Figures 5 and 6 I have shown alternative means for increasing the flexibility of the brake band. Instead of cutting away the flange 7 or the web 8, I propose to separate the web from the flange over a portion of the band desired to be made more flexible, as shown at 18. This separation may be made by means of several methods, but the method disclosed is simply the cutting away of the web where it joins the flange. In this form of band the brake lining preferably extends from one end of the band to the other, as is the usual practice.

In the construction illustrated in Figure 5, the radial pressure device acts on a portion of the web which is separated from the flange and the radial pressure will be distributed over a greater arc than in the construction of Figure 1.

In Figure 7 the radial pressure device 8 is located at the center of the band, an arrangement which gives approximately a uniform brake action in either direction of rotation of the drum.

Being aware of many possibilities of modifying the particular structures herein described without departing from the fundamental principles of my invention, I do not intend that its scope be limited except as set forth by the appended claims.

The feature herein disclosed of having a selected arc or arcs of the lining carrying flange of a "band" type of brake shoe unconnected with the reinforcing web is broadly claimed in my co-pending application Serial No. 595,260.

Having fully described my invention, what I claim as new and desire to secure by Letters Patent of the United States is:

1. In braking apparatus, the combination of a rotatable brake drum, a flexible brake band adapted to cooperate therewith, anchor means for the band intermediate the ends thereof, brake lining secured to the band, and means for applying the band to the drum, said brake band being free of lining over that portion of the band forward of the anchor means where during brake application the pressure between the band and the drum would be the greatest if the lining were continuous.

2. In braking apparatus, the combination of

a rotatable brake drum, a flexible brake band adapted to cooperate therewith, means for applying the band to the drum, said band having its flexibility increased over that portion of the band where during brake application the pressure between the band and the drum would be the greatest if the band were of uniform flexibility, and brake lining secured to said band except over the flexible portion.

3. In braking apparatus, the combination of a rotatable brake drum, a substantially 360 degree flexible brake band adapted to cooperate therewith, means for applying the free ends of the band to the drum, anchor means located at a point more than 180 degrees from the forward end of the band, and brake lining secured to the band, the brake band being free of lining over that portion of the band which lies intermediate the forward end thereof and the anchor and where during application of the brake the pressure between the band and the drum would be the greatest if the lining were continuous.

4. In braking apparatus, the combination of a rotatable brake drum, a substantially 360 degree flexible brake band adapted to cooperate therewith, means for applying the free ends of the band to the drum, combined anchor and radial pressure producing means located at a point more than 180 degrees from the forward end of the band, and brake lining secured to the band, the brake band being free of lining over that portion of the band which lies intermediate the forward end thereof and the combined anchor and radial pressure producing means and where during application of the brake the pressure between the band and the drum would be the greatest if the lining were continuous.

5. In braking apparatus, the combination of a rotatable brake drum, a substantially 360 degree flexible brake band adapted to cooperate therewith, means for applying the free ends of the band to the drum, anchor means located at a point more than 180 degrees from the forward end of the band, said band having its flexibility increased over that portion which lies intermediate the forward end of the band and the anchor and where during application of the brake the pressure between the band and the drum would be the greatest if the band were of uniform flexibility, and brake lining secured to said band except over the flexible portion.

STEVE SCHNELL.
